UNITED STATES PATENT OFFICE.

MARCUS HOLLANDER, OF BROOKLYN, NEW YORK.

AIR PROPELLER.

Application filed September 11, 1922. Serial No. 537,586.

To all whom it may concern:

Be it known that I, MARCUS HOLLANDER, a citizen of the United States of America, residing at Brooklyn, Kings County, State of New York, have invented certain Improvements in Air Propellers, of which the following is a specification.

This invention relates to propulsion devices for propelling bodies through air or water, and the device is especially adapted to rise vertically from the ground, move horizontally in any desired direction when afloat in the air, and also is adapted for travel on land or navigation in the water.

15 The object of this invention is to make combustible substances such as gasoline, alcohol, or the like, explode and by the force of the explosion to drive out the air contained in a special chamber. The escaping 20 stream of air is directed to strike at an inclined plane, which reaction sets the apparatus in motion.

Another object of this invention is to utilize the atmospheric pressure as a motive 25 power for the purpose described. To accomplish this, I direct a part of the compressed air, together with the products of combustion, to pass between the parallel walls over the upper surface of the inclined 30 plane, whereby by its momentum a partial vacuum is formed. Due to this vacuum the force of the stream at the opposite side of the plane is increased by the pressure of 35 the atmosphere under it.

Another object of this invention is to heat the air in the chamber by the burnt fuel, thereby increasing the expansive force of the air.

In the accompanying drawing, I have 40 shown one form of my invention in which drawing—

Fig. 1 represents a cross-sectional view of an apparatus constructed according to my invention;

45 Fig. 2 is a longitudinal sectional view, taken on line A—A, Fig. 1;

Fig. 3 is a similar view taken on line B—B, Fig. 1;

50 Fig. 4 is a sectional view taken on line T—T, Fig. 3;

Fig. 5 is a similar view taken on line E—E, Fig. 3;

Fig. 6 is an enlarged detail view of the rod or link 22, shown in Fig. 1; and

Fig. 7 is an enlarged sectional view on line 55 C—C, Fig. 1.

Referring to the accompanying drawing, 1 indicates a bottle shaped cylinder. The upper part of it, or the neck, which is cup shaped at the center, as at 2, serves as a 60 combustion chamber, while the lower part forms a compressing chamber. The cylinder 1 is provided with a ring-shaped opening at the bottom as at 38. Within the cylinder 1, I place a ring-shaped piston 18, adapted to 65 reciprocate in the said combustion chamber 10, and connected to a ring-shaped valve 19 by rods 20 which in turn are connected to a center rod 21, reciprocating in the sleeve 37. Piston 18 and valve 19 are ring-shaped for 70 the purpose of enlarging the area of the opening for the admission of the inrushing air and the escape of the exploding gases respectively. The combustion chamber 10 is provided with the air inlet 8, fuel inlet 9, 75 and the spark plugs 10^A and 10^B.

Since the means to produce explosion are not part of my invention, the details, such as carburetors, timers, etc., are not shown in the drawing.

80 The compressing chamber 1 is provided with a plurality of double slots 11, 12 arranged one above the other, each in a horizontal position. Each set of slots is radially situated opposite another set to establish a 85 state of equilibrium.

At the exterior of cylinder 1, at both ends of the horizontal slots 11, 12, parallel walls 15, 16 are secured. The walls are placed perpendicular to the slots 11, 12. Between 90 the slots, I secure an inclined plane 17, the position of which is parallel to the slots but perpendicular to the walls 15, 16, as shown in Figures 4 and 5.

Walls 15, 16 are adapted to direct the 95 course of the stream of the fluids expelled from the chamber, to prevent the expansion of the fluid sideways and also to prevent the surrounding air from penetrating and breaking the vacuum formed between the 100 upper surface of the plane and the upper stream as it will be hereinafter described.

The combustion chamber 10 is provided with two pairs of slots 7 arranged one in

front of the other in a vertical position, each set opposite the other and also with curved planes P P between the slots and parallel to them.

5 At both ends of the slots, at the exterior of the combustion chamber parallel walls 15^A, 16^A are secured in a horizontal position perpendicular to slots 7 and curved planes P P as shown in Fig. 2.

10 To control the flow of the stream, the sliding valves 4 are placed in the nests 3. These valves are pivotally connected to rods 5, which are fulcrumed as at 6. The rods 5 are placed within the reach of the operator.

15 The connecting rod 22 at the end of the piston rod 21 is provided with spring clamps 23 and sockets 24 which are adapted to fit into the pins 24^A, and the flywheel 26^A, the pins 24^A are grooved as at 25 for the reception of the clamps 23, whereby the rod 22 may be easily changed from one pin to the other.

The action of my device is substantially as follows:

20 When fuel and air are sucked in through the inlets 8 and 9 by the action of piston 18 into the combustion chamber 10 and ignited by plugs 10^A, piston 18 and valve 19 will, by the force of the explosion, move outwardly and close the opening 38 at the bottom of cylinder 1 opening simultaneously the combustion chamber 10. Due to the explosion, the air in the lower chamber will be driven out through the horizontal outlets 35 11, 12, 13 and 14 in the direction of arrows 30 and 31. The air, together with the products of combustion, due to the explosion, will escape with great velocity through the slots 11 and 14 and will strike the inclined plane 17, as indicated by arrow 31 and will continue to move in the direction of the dotted line 32.

The air, which will escape through the slots 12 and 13, in the direction of arrow 45 30, will carry away the air from the upper surface of the inclined plane 17, forming a partial vacuum between the stream and the plane, as indicated by arrow E. Due to the 50 vacuum between the stream and the plane, the atmosphere from above will deflect the stream in the direction of the dotted line 34, so that both streams will close together as at 35, so that a vacuum will be maintained between the upper stream and the inclined plane during the flow of the stream, thus reducing the pressure from the upper 55 surface of plane 17 while the atmosphere at the opposite side in addition with the action of stream 31 will force the plane upwards, 60 carrying the cylinder and attachments thereto, such as framework, fuel, etc., with it in vertical direction. When the lower chamber is emptied, valves 19 will partly, by the pressure of the outside atmosphere and 65 partly by the action of the flywheel move

inwardly and close the combustion chamber 10 while fresh air will rush in through opening 38 to again fill the chamber for the next operation.

To propel the machine in a horizontal direction, valves 4—4 are open and a part of the air will escape through the vertical slots or outlets 7—7 and strike the vertical inclined planes p — p , forcing the plane to move horizontally while the horizontal plane 75 will propel the machine vertically.

To propel the machine on the ground or water, that is to say, when no vertical motion is desired, rod 22 is detached from pin 24 and attached to pin 25, thus lengthening 80 the rod and shortening the stroke of the piston, so that the combustion chamber is always kept closed by the piston, thus allowing the expanded gases to escape through the vertical slots 7 only. The action will 85 be the same as above described, to wit, the gas formed by the explosion will be expelled with great speed through slots 7 and strike the vertical inclined planes p — p at one side 90 and form a partial vacuum at the opposite side, producing the result above mentioned.

In order to steer the machine to the right or left, one of the valves will have to be closed, that is to say, to steer to the right, the right valve should be closed, while when the left valve is closed, the machine will turn to the left. It is understood that rods 5—5 and the controlling parts of the explosions (not shown in the drawings) are placed within the reach of the operator. As it is seen from above, when applying rod 22 at pin 25 and keeping the valves closed, the machine will move vertically only, while with open valves the machine will move vertically and horizontally simultaneously. Should rod 22 be attached on pin 24, the machine will move horizontally only. It is understood that this apparatus is so designed to convert the energy created by the explosion into a direct action while the air heated in the 100 chamber will add to the efficiency of the apparatus.

28 indicates means by which the propeller can be attached to anything desired to propel. It should be understood that the stream of the heated fluid can also be applied at one side of the plane only, should the same be directed over the convexed surface of the plane. In addition to the repulsing force of the stream the air above will be rarified by the hot gases, thus reducing the pressure above while the normal atmosphere at the opposite side of the plane will force the plane to move in the direction of the rarified air. It should be distinctly understood that the space between the opening surface of the plane and the upper stream indicated by arrow E in Figure 1 is especially provided to enable the upper stream and the plane which are under the 110 120 125 130

action of the atmospheric pressure due to the vacuum between them to approach each other and to move into the evacuated space. As it is seen, the functions of the exploded 5 fuel are many. It serves as an air compressor compressing the air in the chamber by its expansion force and simultaneously will heat the air in the chamber increasing the efficiency of same. The hot air in combination 10 with the hot gases when directed over the convex surface of the plane will repulse and rarify the air above said planes, thus reducing the pressure of the atmosphere and finally will act direct against the 15 concave surface of the plane which reaction will cause the apparatus to move.

Having described my invention, what I claim and desire to secure by Letters Patent is:—

- 20 1. In an air propeller a bottle-shaped cylinder consisting of combustion and compressing chambers with openings at the bottoms and sides thereof, a piston in the combustion chamber to permit expansion of the combustible substances into the compressing chamber, said expanded substances being adapted to compress the air in said compressing chamber.
- 25 2. In an air propeller a bottle-shaped cylinder consisting of a combustion chamber adapted to have combustible substances exploded therein, a compressing chamber to have a volume of air compressed therein by the discharge from said combustion chamber, said chambers being provided with openings at the bottoms and sides thereof, a ring-shaped piston within the combustion chamber, a ring-shaped valve within the compressing chamber, arranged so as to open one of the chambers by closing the other, and vice versa.
- 30 3. In an air propeller a bottle-shaped cylinder consisting of combustion and compressing chambers with openings at the bottoms and sides thereof, a ring-shaped piston within the combustion chamber, a ring-shaped valve within the air chamber, arranged so as to open one of the chambers by closing the other, and vice versa, and means to operate one of the chambers independent of the other.
- 35 4. In a device of the character described consisting of combustion and compressing chambers, with ring-shaped openings at the bottoms thereof, means to open one of the chambers by closing the other, and vice versa, means to operate one of the chambers independent of the other, a plurality of double slots in the wall of the compressing chamber, arranged one above the other in horizontal position, said slots being radially situated each set opposite the other to balance the reaction of the expelled fluids.
- 40 5. In combination with an air propeller consisting of a combustion chamber adapted to have combustible substances exploded therein, a compressing chamber to have a volume of air compressed therein by the discharge from said combustion chamber, a plurality of sets of slots in the 70 wall of the compressing chamber placed one above the other for the passing of the compressed air through said slots, inclined planes between the double slots at the exterior of the compressing chamber, said 75 planes being arranged parallel with the slots in a horizontal position.
- 45 6. In a device of the character described consisting of combustion and compressing chambers, means in the combustion chamber to compress the air in the compressing chamber, a plurality of inclined planes at the exterior of the compressing chamber, a plurality of pairs of narrow outlets in the wall of the compressing chamber, placed above and 80 under the inclined planes, said outlets being adapted to direct part of the compressed air to flow over the inclined planes and another part of the contents of the chamber to pass under the concave side of the plane. 85
- 50 7. In an air propeller, consisting of combustion and compressing chambers, a plurality of narrow outlets in the walls of said chambers, a plurality of inclined planes between the outlets at the exterior of the chambers and parallel walls on both ends of the planes, said walls being parallel with each other but perpendicular to the inclined planes and slots. 90
- 55 8. In an air propeller the combination of 100 combustion and compressing chambers, a plurality of inclined planes radially situated at the exterior of the compressing chamber, and opposite each other in horizontal positions, narrow outlets in the wall of the compressing chamber arranged above and under the inclined planes, the upper slots being some distance apart from the plane, said space being adapted to enable the upper stream to deflect and the plane to move into 105 said evacuated space, by the pressure of the atmosphere. 110
- 60 9. In an air propeller, consisting of a cylinder, a plurality of inclined planes at the exterior of the cylinder, narrow slots at both 115 sides of the planes, side walls perpendicular to the slots and planes, said walls being adapted to prevent the expansion of the flow sidewise and also to prevent the surrounding air from penetrating and breaking the vacuum between the upper surface of the plane and the upper stream. 120
- 65 10. In an air propeller the combination of 125 combustion and compressing chambers, a plurality of inclined planes at the exterior of the compressing chamber, parallel walls at both ends of the planes, narrow outlets in the wall of the chamber at both sides of the planes perpendicular to the walls, said outlets being adapted to direct part of the com- 130

- 4
- pressed air to pass between the parallel walls and over the convex surface of the planes, and to direct another part of the contents of the chamber to strike at the concave surface 5 of the plane forcing it upward.
11. In an air propeller, the combination of combustion and compressing chambers, means to explode combustible substances within the combustion chamber, two sets of 10 slots in the wall of the combustion chamber, opposite each other, one slot being placed in front of the other and in a vertical position, curved planes between the slots at the exterior of the combustion chamber, parallel 15 to the slots, parallel walls at both ends of the planes at the exterior of the combustion chamber, arranged in horizontal positions perpendicular to the slots and planes.
12. In a combination with combustion 20 chamber, means to explode combustible substances in the combustion chamber, curved planes at the exterior of the chamber arranged one opposite the other in a vertical position, means to direct part of the expanded substance to pass between the parallel 25 walls at the front of the curved planes, said stream being adapted to repulse the air adjacent the front of the planes and also to rarify the air by heating same.
13. In an air propeller, a bottle-shaped 30
- casing consisting of a combustion chamber adapted to have combustible substances exploded therein, means to direct part of the contents of the combustion chamber, to pass in front of curved planes, means to direct 35 another part of the products of the explosion to strike at the concave surface at the rear of the plane, and means to direct another part of the product of the explosion to escape into the compressing chamber, expelling 40 the contents of same by its expanding force.
14. In an air propeller, the combination of a combustion and compressing chamber, narrow outlets in the combustion chamber arranged in a vertical position, sliding valves 45 to open and close said vertical slots, said valves being adapted to control the forward motion of the device and to steer same to the left or right.
15. In a device of the character described 50 consisting of combustion and compressing chambers a plurality of narrow outlets in the wall of the compressing chamber, arranged in horizontal position and one above the other, inclined planes between the narrow outlets at the exterior of the compressing chamber, said inclined planes being adapted 55 to propel the device vertically.

MARCUS HOLLANDER,
